[57] ABSTRACT

A wire connector or terminal block including an arch-shaped pressure lever having two opposite leg portions resiliently deformable and expandable under pressure and a conductor plate mounted opposite the pressure lever, adapted to receive a wire end portion and resiliently hold it between the pressure lever and the conductor plate so that the wire end portion can securely be retained by the pressure lever which becomes resiliently deformable under any vibration or other external forces thereby ensuring better electrical properties of the connected portion.

FIG. I

FIG. 2

FIG. 3

FIG.4

FIG.5

WIRE CONNECTOR

BACKGROUND OF THE INVENTION

There are known a number of wire connectors or terminal blocks. According to one prior art, a wire is fastened to a connector by winding the end portion of the wire around a screw and tightening the screw. In another prior art, a wire is retained on a conductor plate by tightening a screw. However, these present disadvantages since the wire connection easily becomes loose when the connector receives vibrations or other external forces. To avoid this, a spring washer is used, but does not meet the need as envisaged by the present invention.

In view of these, the present invention provides improvements over all the prior arts, in which an arch-shaped pressure lever and a conductor plate are provided to hold the end portion of a wire therebetween. The pressure lever is spring-loaded, and is resiliently deformable under vibrations or shocks, so that when the wire connector receives such vibrations or shocks, it prevents the connected portion of the wire from becoming loose and thus worsening the electrical properties thereof. Rather, it improves such electrical properties under this condition.

BRIEF SUMMARY OF THE INVENTION

According to the invention, a wire connector is provided with an arch-shaped pressure lever opposite a conductor plate, both of which are in a variably spaced relation. The pressure lever is built of resilient metal material. The end portion of a wire is inserted between the two elements of the arch-shaped pressure lever, and is retained there by bringing the pressure lever nearer to the conductor plate by tightening a screw. With further screw tightening, the end portions of the pressure lever are expanded outwardly. This screw tightening is continued until the desired amount of pressure is attained. The amount of the tightening pressure depends on the shape, amount of elastic deformation or stability of the pressure lever, or the thickness of a wire used, and should preferably be over 8 kg/cm when using an arch-shaped pressure lever of 7cm high and 5cm wide built a hardened steel plate 1.2mm thick and 6.2mm wide. A pressure lever constructed according to the invention has two opposite leg portions; the end portions of these leg portions are bent outwardly and are expandable under the screw tightening pressure. The conductor plate is constructed of electrically conductive materials such as copper or copper alloy. The pressure lever and the conductor plate are mounted opposite each other in a variably spaced relationship, so that the distance between the two elements is adjustable by tightening or loosening the screw. This distance can be adjusted by moving either the pressure lever or the conductor plate, or both.

One object of the invention is to provide a wire connector or terminal block incorporating a pressure lever and a conductor plate for holding the end portion of a wire therebetween and maintaining the electrically connected portion in a good condition.

Another object of the invention is to provide improved electrical properties of the connected portion without adversely affecting or lowering the fastening pressure of the pressure lever when the connector or terminal block is wholly subjected to vibrations or shocks.

Still another object of the invention is to provide a connector or terminal block having a pressure lever the lowest end portions of which are outwardly expandable within the range of stability as the end portions are brought in contact with the surface of the a conductor plate, so that the end portion of a wire is resiliently held between the pressure lever and the conductor plate while a tightened screw is maintained at a constant pressure.

BRIEF DESCRIPTION OF THE DRAWING

FIG. 1 is a perspective view of the preferred embodiment of the invention.

FIG. 2 is a perspective view of one preferred embodiment of the invention.

FIG. 3 is a perspective view of the main constituent parts of the same.

FIG. 4 is a side view of another preferred embodiment of the invention.

FIG. 5 is a graph showing variations in electrical contact resistance value with different tightening torques.

DETAILED DESCRIPTION OF THE INVENTION

Now, the invention will be further described by way of examples only by reference to the accompanying drawing.

A pressure lever 3 is formed by an arch having two opposite leg portions, the lowest end portions of which are bent outwardly, and a top ceiling portion 3a having a hole for receiving a screw 1. A base 2 is provided for accomodating a conductor plate 6. The base member 2 has a hole 2b at the top 2a for engaging with the screw 1. The screw 1 passes through the hole at the ceiling 3a to reach the hole 2b for engagement therewith. In this manner, the pressure lever 3 is movably connected by the screw 1 to the base member 2. Two or more sets of the pressure lever 3 and the base member 2 thus combined are arranged in parallel with each other in an electrically isolated housing 8. The base members 2, 2 are arranged in parallel and are connected by a plate 2c on which a conductor plate 6 is mounted in such a manner that its surface is contacted by the two lowest end portions of the pressure levers 3. The screw 1 is loaded with a spring 4 between the top 3a and the top 2a to bias the pressure lever 3 to a normal state or upwardly. The lowest end portions of the lever 3 are then located away from kept clear of the surface of the conductor plate 6 to allow a wire 5 to pass therebetween.

The naked end portion 5a of the wire 5 is passed between the pressure levers 3 and the conductor plate 6 which are normally in a spaced relation to each other as explained above. Turning the screw 1 clockwise advances it toward the top 2a of the base 2 to engage with the internally threaded hole 2b. With such tightening of the screw 1, the pressure lever 3 is forced against the spring 4 bringing the lowest end portions thereof into contact with the wire end portion 5a. Further screw tightening causes the lowest end portions of the lever 3 to press against the portion 5a, and to expand outwardly with the increasing pressure of the lever 3. Such expansion is represented by the change from the dot-dash-lines to the solid lines in FIG. 4. Given vibrations or shocks in this state, the pressure lever 3 tries to stabilize, moving from a position indicated by solid lines to a position indicated by dot-dash-lines in FIG. 4, and naturally the pressure increases so that a better connec-

65

tion can be obtained. This also assures improved electrical properties of the connected portion.

Such improved electrical properties are supported by the following experiments which have been carried out and the results obtained therefrom as indicated in FIG. 5.

Type of Wire Connector : PRE-20 (20 Amp.)	
Test Conditions	
Room Temperature	23.0°C
Humidity	72 %
Amplitude	4mm
Number of Vibrations	2000 CPM
Test Hour	Consecutive 48 hours
Directions of Vibrations	
Back and forth, horizontally and vertically	15
Pressure Lever	Hardened Carbonate Steel Plate 1.2mm thick and 6.2mm wide 7.0cm high and 5.0cm open between the two opposite leg portions.

Under the above test conditions and with different tightening torques of 4, 6, 9 and 12 kg/cm, the test has been effected to obtain values of corresponding electrical contact resistance at the connected portion. The results show that the values are 0.4, 0.3, 0.25 and 0.25 mOhms respectively before giving vibrations while the values are 0.3, 0.2, 0.15 and 0.15 mOhms after giving vibrations. This supports the fact that the electrical properties of the connected portion have remarkably been improved.

Referring now to FIG. 4, the base members 2, 2 are arranged in parallel but are not connected by a plate 2c. This nevertheless serves the purpose of the invention.

In all the embodiments described above, the pressure lever 3 is adapted to move down the screw 1 tightening, but it is possible to move the base member 2 or both the lever 3 and the base member 2. There will be no need of the conductor plate 6 if the plate connecting the base members 2 is made of electrically conductive material.

I claim:

1. A wire connector for conductively connecting wires comprising:

a plurality of arch-shaped base member means comprised of electrically conductive material and arranged in parallel with each other with the open sides opposite each other for allowing said wires to pass therethrough;

first connecting means comprised of conducting material attached to the bases of said plurality of arch-shaped base member means for connecting said base member means to each other and for conductively supporting wires running through said base member means;

arch-shaped pressure lever means above each base member means having two resilient and opposite leg portions at the lowest ends thereof bent outwardly away from each other for fitting over the open sides of said base member means and contacting said wires; and

a second adjustable connecting means for connecting the top of each of said pressure lever means to the top of each of said base member means, whereby adjusting said second connecting means downward will cause said pressure lever means to move toward said base member means and will force said outwardly bent legs of said pressure lever means against said wire and said first connecting means.

2. A wire connector for conductively connecting

10 wires comprising:

a plurality of arch-shaped base member means arranged in parallel with each other with the open sides opposite each other for allowing said wires to pass therethrough;

15 first connecting means comprised of a joining plate attached to the bases of said plurality of arch-shaped base member means for joining said base member means to each other and a conductor plate of electrically conductive material located on said joining plate and running through said open sides of the plurality of base member means for conductively supporting wires running through said open sides;

20 arch-shaped pressure lever means above each base member means having two resilient and opposite leg portions at the lowest ends thereof bent outwardly away from each other for fitting over the open sides of said base member means and contacting said wires; and

25 a second adjustable connecting means for connecting the top of each of said pressure lever means to the top of each of said base member means, whereby adjusting said second connecting means downward will cause said pressure lever means to move toward said base member means and will force said outwardly bent legs of said pressure lever means against said wire and said first connecting means.

30 3. A wire connector as claimed in claim 2 wherein each of said pressure lever means has a hole in the top thereof for receiving said adjustable connecting means; each of said base member means has an internally threaded hole in the top thereof for engaging said adjustable connecting means;

35 and said adjustable connecting means is comprised of a screw running through said hole in said pressure lever means and is engageably threaded into said internally threaded hole in said base member means.

40 4. A wire connector as claimed in claim 3 wherein said adjustable connecting means is further comprised of a spring surrounding said screw between said pressure lever means and said base member means for biasing the pressure lever means away from the base member means.

45 5. A wire connector as claimed in claim 2, further comprising electrically isolated framing means for housing said base member means, said first and second connecting means and said pressure lever means.
